UNITED STATES PATENT OFFICE.

STACY B. HASELTINE, OF CHICAGO, ILLINOIS, ASSIGNOR TO WILLIAM H. MINER, OF CHICAGO, ILLINOIS.

DRAFT-RIGGING FOR RAILWAY-CARS.

1,136,128.

Specification of Letters Patent. Patented Apr. 20, 1915.

Application filed July 7, 1913, Serial No. 777,607. Renewed August 12, 1914. Serial No. 856,486.

To all whom it may concern:

Be it known that I, STACY B. HASELTINE, a citizen of the United States, residing at Chicago, in the county of Cook and State of Illinois, have invented a certain new and useful Improvement in Draft-Rigging for Railway-Cars, of which the following is a full, clear, concise, and exact description, reference being had to the accompanying drawings, forming a part of this specification.

My invention relates to improvements in draft rigging for railway cars.

The object of my invention is to provide a draft rigging of high cushioning capacity both in buff and in draft.

In the drawings forming a part of this specification Figure 1 is a side elevation partly in vertical longitudinal section on line 1—1 of Fig. 2 of a draft rigging embodying my invention. Fig. 2 is a plan view partly in horizontal section on line 2—2 of Fig. 1, and showing the parts in normal position. Fig. 3 is a plan view partly in horizontal section showing the position of the parts of the draft gear when fully compressed in buff. Fig. 4 is a cross section on line 4—4 of Fig. 2, one side, however, having the spring cap removed. Fig. 5 is a plan view partly in horizontal section showing the position of the parts when fully compressed in draft.

Referring to the drawings, 6, 6 represent draft sills or the parts of the car frame to which the draft rigging is applied, said draft sills being provided with rear stop shoulders, 7, 7 and front stop shoulders 8, 8; 9 designates the end sill, 10 the draw bar carry iron, 11 a tie-plate suitably secured to the draft sills, 12 a draw bar, 13 the draft yoke secured to the draw bar, 14 draft gear mounted between the draft sills and within the draft yoke. The front follower 15 engages the front stop shoulders 8, 8, the stop shoulders being extended inwardly from the opposite faces of the draft sills leaving between them a suitable space for the passage of the draw bar and draft yoke. The draft gear 14 comprises an inner shell 16 and outer shell 17 inclosing the inner shell, main springs 18, friction mechanism 19, an internal follower 20, a key 21 and a preliminary spring 22.

The inner shell 16 is preferably cylindrical in shape, open at its forward end and

closed at its rear end by the preferably integral plate 23, the said inner shell being provided at its rear end with lateral outwardly extending wings 24, 24 which perform the functions of a rear follower and are adapted to engage the rear stop shoulders 7, 7. The friction mechanism 19 is mounted within the inner shell and consists of the friction shoes 25 which are preferably three in number and adapted to engage the internal friction face 26 of the inner shell, a wedge 27, having wedging faces 28, said faces equaling in number the friction shoes, there being an anti-friction roller 29 interposed between each wedging face of the wedge 27 and the adjacent friction shoe. The wedge 27 forwardly engages the front follower 15 and is provided with a recess 30 to receive the head 31 of the connecting rod 32, the said connecting rod engaging at its rear end the internal follower 20, the same being provided with a recess 33 to receive the nut 34 of said connecting rod. The internal follower 20 is forwardly provided about its outer edge with a collar 35 within which is mounted the preliminary spring 22, the same being seated at its forward end against the friction shoes 25 and at its rear end against the internal follower 20. The key 21 passes through the transverse slot 36 in the internal follower and through slots 37, 37 in either side of the inner shell, said slots 37 being rearwardly extended to permit the sliding of the key 21 therein on rearward movement of the internal follower relative to the inner shell.

The outer shell 17 is preferably cylindrical in shape and is secured to the internal follower 20 by means of the key 21 which is connected at either end to the outer shell, preferably engaging within slots 38, 38 in the outer shell registering with the slots 37 in the inner shell. Laterally extended from the forward end of the outer shell are the wings 39, 39 at either side. The main springs 18, 18 are mounted at either side of the outer shell between the lateral wings 39 of the outer shell and the lateral wings 24 of the inner shell. The said main springs each preferably consists of an outer spring 40 and an inner spring 41 nested therein.

On rearward movement of the draw bar the front follower 15 forces the friction mechanism rearwardly and compresses the preliminary springs 22 against the internal

follower 20 until the collar 35 thereof engages the friction shoes 25 whereupon the internal follower 20 moves rearwardly drawing rearwardly the outer shell by means of 5 the key 21, thus compressing the main springs between the wings 39 of the outer shell and the wings 24 of the inner shell, the springs meanwhile resisting the inward movement of the friction shoes and the 10 wedge spreading said friction shoes. During the rearward movement of the draw bar the inner shell is stopped by its engagement against the rear stop shoulders 7, and the key 21 slides rearwardly in the slots 37, 37 15 in the said inner shell.

Upon forward movement of the draw bar the friction mechanism engages the front follower 15 which is stopped by the front stop shoulders 8, the draft yoke draws the 20 inner shell forwardly, the pressure of the main springs between the wings 39 of the outer shell and the wings 24 of the inner shell holding the key 21 against the forward ends of the slots 37 in the inner shell while 25 the preliminary spring 22 is compressed, whereupon the internal follower engages the friction shoes. During the compression of the preliminary spring the inner and outer shell travel forward together. After such 30 compression and the engagement of the internal follower against the friction shoes the inner shell travels forward at a greater rate than does the outer shell. The friction shoes are brought into action as they are spread by 35 the wedge against the internal friction faces of the forwardly moving inner shell and resisted by the compressing main springs until on full compression in pulling movement the parts assume the position illustrated by 40 Fig. 5 of the drawing, the key 21 engaging the rear ends of the slot 37, and the front end of the inner shell engaging the front follower.

I claim:

45 1. In a draft rigging for railway cars, the combination of a draw bar, draft yoke, followers, front and rear stop members, with an inner shell, friction mechanism in said shell, an outer shell inclosing the inner shell, a key and main springs, the outer shell being provided with laterally extended wings, the main springs being seated between said wings and the rear follower, the key connecting the outer shell to the mechanism in 50 the inner shell, the outer shell and front stop members being spaced apart, whereby on forward movement of the draw bar the main springs and the friction mechanism are both brought into compression resisting action.

55 2. In a railway draft rigging, the combination of a draw bar, followers, front and rear stop members, and draft yoke with outer and inner reciprocating shells, wings laterally extended from each of said shells,

main springs seated between the wings of the outer shell and the wings of the inner shell, friction mechanism within the inner shell, and a key connecting the outer shell to the friction mechanism in the inner shell, 70 the wings of the outer shell being spaced apart from the front stop members, whereby the main springs and friction mechanism are brought into compression resisting action on both forward and rearward movement of the draw bar.

3. In a draft rigging for railway cars, the combination with a draw bar, front and rear stop members, followers and draft yoke, of outer and inner reciprocating shells, 80 wings laterally extended from each of said shells, main springs seated between the wings of the outer shell and the wings of the inner shell, friction mechanism and an internal follower within the inner shell, and 85 a key engaging the internal follower to the outer shell, the stop members and the wings of the outer shell being spaced apart, whereby the friction mechanism and the main springs are compressed in both forward and 90 rearward movement of the draw bar.

4. In a draft rigging for railway cars, the combination with front and rear stop members, a draw bar, draft yoke and followers, of an outer shell and an inner shell reciprocating therein, each of said shells being provided with laterally extended wings, main springs seated between the wings of the outer shell and the wings of the inner shell, a wedge, friction shoes and an internal follower within the inner shell, a preliminary spring seated between the internal follower and the friction shoes, and a key engaging the internal follower to the outer shell, the wings of the outer shell being spaced apart 100 from the stop members, whereby on forward movement of the draw bar the main springs and friction mechanism are both brought 105 into compression resisting action.

5. In a draft rigging for railway cars, the combination of front and rear followers, a draw bar, stop members and draft yoke, with an outer shell provided with lateral wings, an inner shell reciprocating therein and engaging the rear follower, main springs at either side of the outer shell seated between the wings of the outer shell and the rear follower, friction shoes, a wedge and internal follower within the inner shell, a key engaging the internal follower to the outer shell, the inner shell being provided with slots for the passage of said key, and the wings of the outer shell being spaced apart from the front stop members to permit the forward movement of said wings 115 and compression resisting action of the friction shoes and wedge on forward movement 120 of the draw bar.

6. In a draft rigging for railway cars, the combination of a draw bar, followers, 130

stop members and draft yoke, with inner and outer reciprocating shells, laterally extended wings for the outer shell, main springs mounted at either side of the outer shell and between the wings of the outer shell and the rear follower, friction mechanism and an internal follower within the shell, a key passing through the internal follower and engaging the outer shell, the wings of the outer shell being spaced apart from the front stop members to permit the forward movement of said wings, and compression resisting action of the friction mechanism in forward movement of the draw bar.

7. In a draft rigging for railway cars, the combination of a draw bar, followers, stop members and draft yoke, with an inner shell, friction mechanism in said shell, an outer shell surrounding the inner shell, a key, an internal follower and main springs, the outer shell being provided with laterally extended wings, the main springs being seated between said wings and the rear follower, the key connecting the outer shell to the internal follower, a space being provided between the wings of the outer shell and the front stop members, whereby throughout forward movement of the draw bar the key and internal follower transmit the pressure of the main springs to the friction mechanism, bringing the friction mechanism into compression resisting action.

8. In a draft rigging for railway cars, the combination with the draw bar, followers,

stop members and draft yoke, with outer and inner reciprocating shells, wings extended from the outer shell, main springs seated between said wings and the rear follower, friction mechanism within the inner shell, means connecting the friction mechanism to the outer shell, a space being provided between the wings of the outer shell and the front stop member to permit the free forward movement of the said wings, and compression resisting action of the friction mechanism in forward movement of the draw bar.

9. In a draft rigging for railway cars, in combination, a draw bar, front follower, front and rear stop members, draft yoke, an inner shell, an outer shell surrounding the same, friction mechanism in the inner shell, wings laterally extended from each of said shells, main springs seated between said wings, and means connecting the friction mechanism to the outer shell, there being a space between the wings of the outer shell and the front stop members, whereby on forward movement of the draw bar the outer shell moves forwardly and the inner shell moves forwardly within the outer shell, the tension of the main springs being applied to the friction mechanism, bringing the same into compression resisting action.
